UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,983, dated July 1, 1890.

Application filed April 16, 1890. Serial No. 348,108. Term of patent 3½ years.

To all whom it may concern:

Be it known that I, HENRY O. SCHMIDT, a citizen of the United States, residing in New York, in the county and State of New York, 5 have invented and produced a new and original Design for Cane or Umbrella Handles, of which the following is a specification, reference being had to the accompanying drawing, forming part thereof.

10 The drawing illustrates a side elevation of a cane or umbrella handle embodying my new design.

15 A is the body part, and extends upwardly into the crook B. The lower part of A is relieved by a band F of ornamental work. The crook and body part are formed with the ornamentation C E, which consists of a series of oblique bands with the appearance of being plaited or interlaced. The parts C extend obliquely backward upon the sides and branch from a central band D at the top, and both

parts D and E are plain. The parts E are ornamental or ribbed and extend obliquely upward from the under edge of the handle. At the lower end of the handle these parts C and E terminate in continued bands C' and E', crossing, as shown. The spaces G between the parts C and E are shaded or otherwise finished to give relief to the parts C and E. 25

The handle may be made of any suitable 30 material.

Having now described my new design, what I claim as new, and desire to secure by Letters Patent, is—

35 The design for umbrella or cane handles, substantially as herein described and shown.

In testimony of which invention I have hereunto set my hand.

HENRY O. SCHMIDT.
